UNITED STATES PATENT OFFICE.

ABRAHAM NEWMAN, OF CHICAGO, ILLINOIS.

DESIGN FOR A MARKING-KEY FOR WATCHMEN'S CLOCKS.

SPECIFICATION forming part of Design No. 34,563, dated May 28, 1901.

Application filed March 18, 1901. Serial No. 51,793. Term of patent 7 years.

To all whom it may concern:

Be it known that I, ABRAHAM NEWMAN, a citizen of the United States of America, and a resident of Chicago, county of Cook, and State of Illinois, have invented and produced a new and original Design for Marking-Keys for Watchmen's Clocks, of which the following is a specification.

My invention relates to a design for a marking-key for watchmen's clocks, and has for its object the production of a new and original form for such keys.

My invention is illustrated in the accompanying drawings, in which—

Figure 1 is an enlarged perspective view of the key, and Fig. 2 is an end elevation showing the shape of the flange or bit in its relationship to the shank or stem.

In the said drawings, S represents the shank or stem of the key, and F a flange or bit extending from one side of the stem S. The flange F is bent to substantially a right angle, as shown at B, and on the edge of the part so

bent is formed an indicating character. The face of the indicating character lies in a plane 25 that is parallel with and adjacent to the stem S, as is shown by the line X X in Fig. 2.

The essential features of my design consist of a key-stem having a flange projecting from the side thereof, said flange being bent so that 30 the outer portion forms an angle with the inner portion, said outer portion having an indicating character formed on its extreme edge, and said character having its face lying in a plane that is parallel with and passes adjacent to the stem. 35

What I claim is—

The design for a marking-key for watchmen's clocks, substantially as shown and described. 40

Signed at Chicago, Illinois, this 15th day of March, 1901.

ABRAHAM NEWMAN.
